OIL CAN

Carl H. Leonard, Wakefield, Nebr.

Application April 17, 1937, Serial No. 137,558

2 Claims. (Cl. 221—48)

This invention relates to dispensing devices and more particularly to an improved type of oil can.

An object of this invention is to provide an improved oil can which is so constructed that pressure on the flexible bottom thereof will forcibly eject oil in desired quantities through the spout.

10 Another object of this invention is to provide a valved spout for an oil can which is adapted to admit air into the can as the oil is forcibly ejected therefrom.

A further object of this invention is to provide an improved spout for an oil can which may be attached to a conventional oil can for the purpose of forcibly ejecting the oil from the can as the bottom is flexed.

With the foregoing and other objects in view, the invention will be more fully described hereinafter, and will be more particularly pointed out in the claims appended hereto.

In the drawing, wherein like symbols refer to like or corresponding parts throughout the several views.

25 Figure 1 is a vertical section partly broken away and in side elevation of an oil can constructed according to an embodiment of this invention.

Figure 2 is a bottom plan of the closure of
30 the discharge tube in section.

Referring to the drawing, the numeral 10 designates generally a liquid receptacle which is adapted to receive oil or the like. This receptacle 10 is provided with a relatively flexible bottom 11 and a reduced threaded neck 13. Preferably, the receptacle 10 tapers upwardly and is substantially conical in configuration, although I do not wish to be limited to the particular configuration of the body of the can 10.

40 In order to provide a means whereby oil or
other liquids may be readily dispensed from the
can 10, I have provided a spout 12 of suitable
length having, in the present instance a curved
outer end portion 14. This spout 12 at its inner
45 end is secured to a chambered plug or closure 15
provided with peripheral threads 16 and a flange
17. The threads 16 are adapted to engage the
threaded neck 13 of the receptacle 10 so as to
50 tightly secure the spout 12 on the upper end of
the receptacle 10. The chambered plug 15 com-
prises an inner wall 18 and an outer wall 19 pro-
vided with an annular raised portion 20 engaging
about the inner end of the spout 20 which is pro-
55 vided with an air vent 21. The inner wall 18 is
provided with a vent 22 and a ball valve 23 is

adapted to engage against the vent 22, being held thereagainst by means of a spring 24 having an eye 25 at one end thereof upon which the ball 23 is adapted to seat. The other end of the spring 24 is provided with one or more loops and the extremity 26 of the spring 24 is soldered or otherwise fastened to the inner bottom 18 so that the ball 23 will be yieldably supported in a position to close the vent 22.

An elongated tube 27 is formed integral with the spout 12 and extends through the inner bottom 18 and the outer wall 19 of the plug 15 and is preferably bent longitudinally in a manner such that the inner and thereof will be positioned closely adjacent the junction between the bottom 11 and the side wall of the can or receptacle 10.

In the use and operation of this dispensing device, the closure 15 is unthreaded from the neck 13 and the receptacle 10 filled with the desired liquid which, in the present instance is oil and the closure 15 is then replaced. The inner open end of the discharging tube 27 will be positioned closely adjacent the bottom 11 at the periphery thereof so that when the bottom 11 is flexed inwardly to force oil out of the receptacle 10, the movement of the bottom 11 will not effect the passage of oil from the receptacle 10 into the inner or open end of the discharge tube 27. 20 25

When the bottom 11 flexes outwardly of the receptacle 10 a partial vacuum will be formed in the receptacle 10 which is relieved by atmospheric pressure, unseating the valve 23 and permitting air to pass from the vent 21 through the hollow plug or closure 15 and then pass the opened valve 23 into the interior of the receptacle 10. The check valve 23 will yieldingly close when the air pressure inside the can 10 is substantially equal to the atmospheric pressure. Through the construction of a can of this type the flexing of the bottom 10 will, at all times, discharge oil through the spout 12 irrespective of the angular position of the can so long as the inner open end of the discharge tube 27 is submerged in the oil. Preferably, the curved end portion 14 of the spout 12 is directed in the same direction as the inclination of the inner portion of the tube 27 so that when oil is being discharged from the receptacle 10, the user of the device will naturally turn the can so that the curved portion 14 will be downwardly and this will then simultaneously position the inner open end of the discharge tube 27 at the bottom of the liquid so that irrespective of the quantity of oil in the can 10, oil will at all times be ejected upon flexing of the bottom due to the fact that

when the bottom 11 is flexed pressure is set up inside the can 10 which can only be relieved by the ejection of oil through the discharge tube 27 and the spout 12.

5 It is, of course, understood that various changes and modifications may be made in the details of construction and design of the above specifically described embodiment of this invention without departing from the spirit thereof, such changes 10 and modifications being restricted only by the scope of the following claims.

I claim:—

1. An oil can comprising a receptacle, a flexible bottom carried by said receptacle, a threaded neck 15 carried by said receptacle, a hollow closure threadably engaging said neck, said closure having vent means therethrough, a spout, a discharge tube integral with said spout and extending through said closure and terminating at a

point adjacent the junction of said bottom and the side wall of the receptacle, a ball valve engaging said vent means, and a resilient arm fixed at one end to said closure and provided with an eye at the other end engaging said valve to normally hold said valve in closed position. 5

2. A dispensing means for a receptacle having a flexible bottom comprising an elongated spout, a threaded closure carried by said spout provided with a vent opening, an elongated longitudinally 10 bent discharge tube integral with said spout and adapted to be disposed interior of the receptacle with the inner open end adjacent the bottom thereof, a spherical valve engaging said opening, a resilient arm secured at one end to said closure, 15 and an eye carried by the opposite end of said arm engaging said valve to normally hold said valve in closed position.

CARL H. LEONARD.
